US0D1056907S

(12) **United States Design Patent** (10) **Patent No.:** **US D1,056,907 S**
(45) **Date of Patent:** **** Jan. 7, 2025**

(54) **CASE FOR AUGMENTED REALITY AND MIXED REALITY DEVICES**

(71) Applicant: **Shenzhen Longda Weiye Technology Co., Ltd.**, Shenzhen (CN)

(72) Inventor: **Yulin Xie**, Shenzhen (CN)

(73) Assignee: **Shenzhen Longda Weiye Technology Co., Ltd.**, Shenzhen (CN)

(**) Term: **15 Years**

(21) Appl. No.: **29/878,256**

(22) Filed: **Jun. 19, 2023**

(51) LOC (15) Cl. **14-02**

(52) U.S. Cl.

USPC **D14/372**

CLAIM

The ornamental design for a case for augmented reality and mixed reality devices, as shown and described.

DESCRIPTION

FIG. 1 is a top, front perspective view of a case for augmented reality and mixed reality devices showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom, rear perspective view thereof.

The broken lines in the drawings show portions of the case for augmented reality and mixed reality devices that form no part of the claimed design.

1 Claim, 8 Drawing Sheets
